UNITED STATES PATENT OFFICE

GEORGE WILTON, OF HENDON, ENGLAND.

FURNACE.

1,081,073.

Specification of Letters Patent.

Patented Dec. 9, 1913.

Application filed June 14, 1912. Serial No. 703,600.

To all whom it may concern:

Be it known that I, GEORGE WILTON, of "Bargoed" Station Road, Hendon, in the county of Middlesex, England, a subject of the King of Great Britain and Ireland, engineer, have invented certain new and useful Improvements in or Relating to Furnaces, of which the following is a specification.

10 This invention relates to furnaces of the kind wherein a perforated surface is formed by a series of transverse sections or members which when assembled form blast pipes or chambers. The sections are in some cases 15 supported upon a trough.

According to this invention I provide in the base of the flue or furnace a trough or cradle (hereinafter referred to as the "trough") made of a determined length 20 and with raised ends so arranged that the several transverse sections which are to form the blast pipes or passages can be fitted together in a row or in the trough without requiring any through bolts for 25 holding the parts together, and in such manner that any section can be lifted out and replaced or renewed. The sections are each provided with downwardly projecting webs disposed longitudinally so as to support the 30 grate surface of the sections above the trough and also form the division walls between the passages through which the blast is directed. The trough also is made in one continuous length and is watertight 35 throughout its length so that any water leaking through from the steam at the inlet end of the blast pipes will be received in the trough and will not come in contact with the boiler flue.

40 In some cases water may be placed in the trough and the blast may be provided by a suitable fan or blower instead of a steam jet, in this case the water in the trough provides the necessary cooling means both by 45 its presence and the steam generated therefrom.

The accompanying drawings illustrate one construction made in accordance with the present invention.

50 Figure 1 is a section on the line $w-w$ of Fig. 2, parts being broken for the sake of clearness. Fig. 2 is a section on the line $y-y$ of Fig. 1. Fig. 3 is a section on the line $z-z$ of Fig. 1. Fig. 4 is a section on the line $v-v$ of Fig. 1. Fig. 5 is a view similar to Fig. 2 showing a modified construction.

In the base of the flue a is fitted a trough t consisting of a plate made to the shape of the flue and having at its ends turned up parts t' t'' . Disposed above the trough and covering in the same are the sections c a number of which are assembled together in or on the trough to form the blast pipes, or passages d' d'' d''' . For this purpose the sections are provided with downwardly extending webs e which rest in sockets or against retaining ribs f running along the base of the trough.

The sides of the sections terminate close against the sides of the flue and meet the edge of the trough. The three blast passages d' d'' d''' are thus formed, the center passage d'' being formed by the trough at its base, the tops and sides by the sections and the downwardly extending webs e . The two side blast passages d' and d'' are formed by the sections on the top, the web on the one side, the trough t on the other. As a modification the trough may be made shallower and the boiler flue may form part of one side of the outer blast furnace.

The several sections are assembled in the trough t which is made to contain a certain number of sections, and the steam blast nozzles h are provided with an end plate h' coupling several blast nozzles together when there are more than one. The said plate h' fits onto the end plate t' of the trough which comes against the first of the blast pipe sections c .

In use the fuel is piled up in the flue a as indicated by the dotted lines x in the manner usually adopted with this type of furnace and the blast is operated by steam in the usual way. Any water which may drip from the blast pipe is received in the trough t and is gradually evaporated or may be drawn off.

Fig. 3 shows the end plate t' of the trough in front elevation.

To assist in the consumption of the smoke I employ that type of supplementary air supply where the air, sometimes heated, is discharged from a chamber around the furnace door and to this end I provide an auxiliary air blast pipe m Figs. 1 and 4 the said pipe being carried up around the fire door, the air being led thereto by pipes m' from the blast pipes d' d'' . The pipe m discharges the air forward toward the bridge, whereby during intervals when a large quantity of smoke is made the blast in the

5 pipes d' d^2 d^3 may be lessened or eased down by drawing off a portion of the air blast from within the blast pipes and discharging the said portion of air through the auxiliary blast pipe m thereby assisting the proper combustion of the smoke. The auxiliary blast can be regulated by a piston valve m^2 which determines the quantity of air which is drawn off from within the blast 10 pipes m .

What I claim and desire to secure by Letters Patent is:—

15 1. In a furnace, in combination, a trough member and a plurality of perforated grate members extending transversely thereof, each of said grate members being provided with a depending web extending in the direction of the length of the trough, the web of each member being in alinement with the webs of adjacent members whereby the 20 space between the grate members and the trough member will be divided into a plurality of passages.

25 2. In a furnace, in combination, a trough member and a plurality of perforated grate members extending transversely thereof, each of said grate members being provided

30 with a depending web extending in the direction of the length of the trough adapted to engage said trough member, the web of each member being in alinement with the webs of adjacent members whereby the space between the grate members and the trough member will be divided into a plurality of passages.

35 3. In a furnace, in combination, a trough member and a plurality of perforated grate members extending transversely thereof, each of said grate members being provided with a depending web extending in the direction of the length of the trough, the web of each member being in alinement with the webs of adjacent members whereby the space between the grate members and the trough member will be divided into a plurality of passages, and means for introducing a blast of air into one of said passages.

40 45 In testimony whereof I have signed my name to this specification in the presence of two subscribing witnesses.

GEORGE WILTON.
